UNITED STATES PATENT OFFICE.

VALENTINE C. LUPPERT, OF WILLIAMSPORT, PENNSYLVANIA.

FRICITION-HINGE CONSTRUCTION.

1,198,937.

Specification of Letters Patent. Patented Sept. 19, 1916.

Application filed March 10, 1916. Serial No. 83,368.

To all whom it may concern:

Be it known that I, VALENTINE C. LUPPERT, a citizen of the United States, and a resident of Williamsport, in the county of 5 Lycoming and State of Pennsylvania, have invented certain new and useful Improvements in Friction-Hinge Construction; and I do hereby declare the following to be a full, clear, and exact description of the invention, such as will enable others skilled 0 in the art to which it appertains to make and use the same.

This invention relates to improvements in friction hinge constructions and more 5 particularly to means for pivotally supporting mirrors between the standards of frames on dressers, chiffoniers and other articles of furniture,—the objects of the invention being to provide a friction hinge construction which may be easily adjusted to offer any desired frictional resistance to the turning of the mirror; to so construct the device that the adjusting spindle shall be relieved of the weight of the mirror, and to provide 0 5 friction hinge devices which shall be adaptable to frames having standards of different widths or thicknesses.

With these and other objects in view, the invention consists in certain novel features 0 of construction and combinations of parts as hereinafter set forth and pointed out in the claims.

In the accompanying drawings, Figure 1 is a vertical sectional view illustrating an 5 application of my improvements; Fig. 2 is a view partly in horizontal section; Fig. 3 is an end view, with the frame 1 omitted; Fig. 4 is an end view of the member which is mounted in the stationary standard; Fig. 5 is a view of the bracket 3, and Figs. 6, 7, 8 and 9 are views illustrating modifications.

1 represents a portion of a mirror frame, and 2 indicates a part of one of the supporting standards.

5 In the form of the invention shown in Fig. 1, I employ an angle bracket 3, one member, 4 of which is perforated for the accommodation of fastening devices for securing the same to one face of the mirror frame 1, while the other member 5 of said angle bracket enters between the mirror frame and the adjacent supporting standard 2. The member 5 of the angle bracket is formed with flaring flanges 6—7^c which 0 5 coöperate to provide a seat having flaring walls, for a similarly shaped flanged disk or

head 7 at one end of a sleeve 8, and said member 5 of the angle bracket is provided with a central hole 9 for the accommodation of the sleeve 8. The sleeve 8 and head 7 are 60 rigidly secured together, said head having a hole to receive the sleeve and the latter being provided with a curled or flanged end 10 to engage said head. The sleeve 8 enters a hole 11 in the standard 2, and is capable of 65 limited longitudinal movement therein, but is prevented from turning by means of fins 12 which engage the wall of the hole 11. The free end portion of the sleeve, on which the fins are formed, is somewhat contracted 70 in size and this contracted portion is internally threaded as shown at 13. A spindle 14 is mounted to turn in the hole in the standard 2, and a considerable portion of this spindle is threaded, as shown at 15,— 75 said threaded portion passing through the sleeve 8 and engaging the threads in the contracted end thereof. The free outer end of the spindle is provided with a head or knob 16 having a shoulder 17 which bears 80 against a suitable washer 18 on the outer face of the standard 2.

When the parts are assembled, the mirror will be pivotally supported between the fixed standards, and the frictional resistance to 85 the turning of the mirror may be increased or decreased, as desired, by turning the spindle 14 to cause the flanged disk or head 7 on the sleeve 8 to engage the flaring or cup-shaped seat in the bracket 3, with more 90 or less pressure. It will also be observed that the weight of mirror is sustained by the sleeves 8 and hence the adjusting spindles are entirely relieved of all weight and strain. Again, by the employment of a bearing such as above described, I am enabled to use an adjusting spindle having a long threaded portion, and hence the device is readily adaptable to standards of various widths or thicknesses, without necessity for 100 making spindles of various lengths to accommodate standards of different dimensions.

If desired, the member 5 of the bracket 3 may be made flat, as shown at 5^a, Fig. 6 and instead of employing a head having flaring flanges as above described, a head 7^a having a plain peripheral flange 7^b, may be secured to the sleeve, so that the free edge of said flange will bear with frictional pressure 110 against the flat member 5^a of bracket 3.

The head or disk may be omitted from

the sleeve 8, and the curled or upset flange 10 on the end of the sleeve utilized to form the head on the sleeve which effects frictional connection between the sleeve 8 and bracket 3 as shown in Fig. 7. In this form of the invention, the member 5 of the bracket 3 may be provided with a flange 5^b to close the flanged or headed end of the sleeve.

Instead of employing an angle bracket 3
10 having a member 4 to be secured to the outer face of the standard, I may use a bearing bracket 19, such as shown in Fig. 8. This bracket consists merely of a plate to be secured to the edge of the mirror frame, and
15 having an outwardly pressed boss 20 to receive the head or flange on the sleeve, and said boss is slotted as at 21 to accommodate the sleeve 8.

In each of the forms of the invention,
20 the bearing bracket may be slotted to receive the sleeve 8 as shown in Fig. 9 so that the mirror may be readily removed and replaced when desired.

Various changes might be made in the de-
25 tails of my invention without departing from the spirit thereof or limiting its scope, and hence I do not wish to restrict myself to the precise details herein set forth.

Having fully described my invention what
30 I claim as new and desire to secure by Letters-Patent, is:—

1. A friction hinge construction comprising a bearing bracket, a bearing sleeve con-

stituting a pivotal support for said bracket, said sleeve having a contracted internally 31 threaded portion near its end farthest removed from the bearing bracket and a friction head at the other end of said sleeve to engage said bracket, and a manually operable spindle passing through the sleeve and 41 having a threaded portion to engage the threaded portion of the sleeve.

2. A friction hinge construction, comprising a bearing bracket having a seat having flaring walls, a bearing sleeve constituting a pivotal bearing for said bracket, a disk secured to said sleeve and having a flaring flange to have frictional engagement with the flaring wall of the seat on said bracket, and means for moving said sleeve longitudinally to regulate the frictional connection between said sleeve and bracket.

3. A friction hinge construction, comprising a bearing bracket, a bearing sleeve constituting a pivotal support for the bracket, a flanged disk secured to said sleeve and having frictional connection with said bracket, and means for adjusting said bearing sleeve longitudinally.

In testimony whereof, I have signed this specification in the presence of two subscribing witnesses.

VALENTINE C. LUPPERT.
